ATTORNEY.

UNITED STATES PATENT OFFICE.

KARL FRIED, OF NEW ORLEANS, LOUISIANA.

DEHYDRATING APPARATUS.

Application filed July 29, 1927. Serial No. 209,371.

My invention relates to dehydrating apparatus.

An important object of the invention is to provide apparatus of the above mentioned character which may be employed to dry fruit, vegetables or the like.

A further object of the invention is to provide apparatus of the above mentioned character, so constructed that the drying medium, such as heated air, is caused to travel in a closed circuit about the material to be dried, and the moisture removed from the heated air without allowing the escape of the heated air, thereby economizing in the operation of the apparatus.

A further object of the invention is to provide apparatus of the above mentioned character which is simple in construction, strong, durable and not liable to derangement.

Other objects and advantages of the invention will be apparent during the course of the following description.

In the accompanying drawings, forming a part of this specification, and in which like numerals are employed to designate like parts throughout the same,

Figure 1 is a central vertical longitudinal section through apparatus embodying my invention, parts in elevation for the purpose of illustration,

Figure 2 is an enlarged section through one of the movable doors affording access to the tray,

Figure 3 is a horizontal section taken on line 3—3 of Figure 1,

Figure 4 is a vertical section taken on line 4—4 of Figure 1,

Figure 5 is a front elevation of the apparatus, and,

Figure 6 is a detailed section taken on line 6—6 of Figure 3.

In the drawings, wherein for the purpose of illustration, is shown a preferred embodiment of my invention, the numeral 10 designates a casing or housing, which is vertically arranged and is preferably rectangular in horizontal cross section. This casing is closed, and is included in an enclosed circuit for the continuous circulation of a drying medium, such as heated air.

Arranged in the forward portion of this casing are inclined tracks 11, extending downwardly toward the front end of the casing. These tracks are attached to stationary uprights 12, arranged in the cas-

ing, and the tracks 11 are spaced from the side walls of the casing, providing passages for the free travel of the heated air. Mounted to slide longitudinally upon the tracks 11 are trays, embodying frames 13, and bottoms 14, which are foraminous and preferably made of wire net, although any other suitable material may be used. The tracks lead to openings 15 in the front wall 60 of the casing and the trays are adapted to be moved into and out of the casing through these openings. Each opening is covered by a vertically swinging door 16, hinged at its top, as shown at 17. Each door carries a pivoted handle 18, having cranks 19', which aid in opening the doors. As soon as the trays are completely introduced into the casing or removed therefrom, the door is released and it will drop to the closed position, 75 thereby preventing, as much as possible, the escape of the heated air.

Disposed in the upper end of the casing 10 and spaced from its top is an inclined partition 19, extending for the entire width 80 of the casing and forming a gas-tight joint with the sides thereof. This partition extends toward the front end of the casing and provides a passage 20, the upper forward end of which is open, as shown. Connected with the lower rear end of the partition 19 is a vertical partition 21, attached to the partition 19 and extending for the entire width of the casing 10 and forming a gas-tight joint with the sides of the casing. The partition 21 forms with the adjacent rear end wall of the casing 10 a depending vertical passage 22, in free communication with the passage 20. The numeral 23 designates an intermediate vertical transverse partition or wall, extending for the entire width of the casing 10 and having gas-tight joints with the sides thereof and with the partition 19. A bottom wall 24 is arranged between the end wall of the casing 10 and the intermediate partition 23, and extends for the entire width of the casing 10, and forms a gas-tight joint with the sides of the casing and the co-acting walls. The bottom wall 24 is preferably inclined 90 rearwardly and is provided in its lower end with a drain pipe 25, extending to the exterior of the rear of the casing 10 and equipped with a cut-off valve 26. The partition 23 and bottom 24 and associated walls 95 provide a condensing chamber 27, extending for the entire width of the casing 10, and

100

105

110

the lower portion of this condensing chamber is in communication with the passage 22, as shown.

The partition 23 extends downwardly beyond the bottom wall 24 and is connected at its lower end with a bottom wall 28, forming a closed fan chamber 29. Mounted within the fan chamber 29 is a rotary blower or centrifugal fan 30, having an outlet at its periphery in communication with a discharge pipe 31, extending through the partition 23, and having a flaring outlet end 32, arranged adjacent to and below the lowermost tray. The rotary blower is driven by a motor 33, arranged exteriorly of the casing 10, as shown.

The numeral 34 designates a vertically arranged suction pipe, extending longitudinally through the condensing chamber 27, adjacent its forward side, and terminating at an elevation adjacent to and spaced from the closed top of the condensing chamber, as shown. The pipe 34 extends through the bottom 24, having a gas-tight joint therewith, and leads into a suction pipe 35, connected with the central intake of the rotary blower. The pipe 34 is equipped with a cut-off valve 36, which is operated by a rod 37, extending to the exterior of the casing, and equipped with a handle 38. The pipe 34 is preferably of smaller diameter than the pipe 35, and I have found that satisfactory results may be obtained by having the pipe 34 one inch in diameter and the pipe 35 four inches in diameter, while the invention is in no sense restricted to these dimensions. The pipe 35 extends forwardly of the partition 23 and is continued in the form of a pipe 39, preferably of the same diameter, and having an intake 40.

Arranged within the condensation chamber 27 are inclined baffles 27', having apertures 28', preferably one-thirty-second of an inch in diameter and punched upwardly from the lower sides of the baffles, as shown.

Arranged in the bottom of the casing 10 is a steam heating coil 41, for supplying heat to the lower portion of the casing, while any other suitable form of heating means may be employed.

The operation of the apparatus is as follows:

The trays are properly filled with the articles to be dried, such as fruits, or vegetables, and introduced into the casing. The centrifugal fan 30 is set into action, while the steam coil 41 is delivering heat to the bottom of the casing. The air passes from the flaring end of the discharge conduit 31 into the lower portion of the casing 10, and traveling over the heating coil 41, is heated and passes upwardly between or through the trays. Some of this air passes upwardly and is drawn into the passage 20 while the major portion of the air is drawn in through

the suction pipe 40 and directly returned to the centrifugal fan. When the air passes between or through the trays it dries the fruit or vegetables and becomes laden with moisture obtained from the same. A portion of this moisture laden air passes through the passage 20, as stated, and is drawn through the passage 22, and into the condensing chamber 27 and is there deprived of its moisture, which is condensed in the bottom of the condensing chamber. This air is now drawn through the suction pipe 34 and returned to the intake of the centrifugal fan. It is thus seen that the air is caused to travel in a closed circuit within the casing, and during its travel it passes in contact with the material to be dried to remove the major portion of the moisture therefrom, and upon further travel of the air, in the closed circuit, it is deprived of the major portion of its water, and returned to the casing to repeat the operation. By this means the drying may be effected with the least amount of supply heat, and hence a substantial economy is effected in the operation of the machine. It is desired to have the air travel relatively slowly through the condensing chamber 27, and to effect this, and to feed a suitable amount of air to the intake of the fan, the suction pipe 39 is provided, preferably having a greater diameter than the pipe 34.

It is to be understood that the form of my invention, herewith shown and described, is to be taken as a preferred example of the same, and that various changes in the shape, size and arrangement of parts may be resorted to without departing from the spirit of my invention, or the scope of the subjoined claims.

Having thus described my invention, I claim:

1. In a dehydrating apparatus of the character described, a casing, upstanding supporting means within the casing for the material to be dried, a condensing chamber within the casing upon one side of the supporting means, means providing a passage arranged above the supporting means and leading into the bottom of the condensing chamber, a rotary fan, an outlet pipe connected with the fan and leading into the casing below the supporting means, a suction pipe in communication with the top of the condensing chamber and leading to the intake of the fan, and a second suction pipe leading into the casing at an elevation near its center and in communication with the intake of the fan, the second named suction pipe having a greater diameter than the first named suction pipe.

2. In a dehydrating apparatus of the character described, a substantially vertical casing, supporting means within the casing for the material to be dried and extending

throughout the major portion of the vertical length of the casing, a substantially vertical condensing chamber within the casing upon one side of the supporting means, 5 means providing a passage arranged above the supporting means and leading into the bottom of the condensing chamber, a rotary fan, an outlet pipe connected with the fan and leading into the casing below the supporting means, a suction pipe in communication with the top of the condensing chamber and leading to the intake of the fan, and a second suction pipe leading into the casing 10 at an elevation near its center and in communication with the intake of the fan.

3. In a dehydrating apparatus of the character described, a substantially vertical casing, substantially vertical supporting means within the casing for the material

to be dried and extending throughout the major portion of the vertical length of the casing, a substantially vertical condensing chamber within the casing, means for receiving vapors from the top of the casing and conducting the same into the bottom of the condensing chamber, a rotary fan, an outlet pipe connected with the fan and leading in the casing adjacent to the lower end of the supporting means, a suction pipe in communication with the top of the condensing chamber and leading into the intake of the fan, and a second suction pipe leading into the casing at an elevation near its center and in communication with the intake of the fan. 35

In testimony whereof I affix my signature.

KARL FRIED.
